UNITED STATES PATENT OFFICE.

FREDERICK D. WARNER, OF MIDDLETOWN, NEW YORK.

MECHANICAL STARTER FOR INTERNAL-COMBUSTION ENGINES.

1,389,108.

Specification of Letters Patent. Patented Aug. 30, 1921.

Application filed March 29, 1920. Serial No. 369,725.

To all whom it may concern:

Be it known that I, FREDERICK D. WARNER, a citizen of the United States, residing at 82 East avenue, Middletown, in the county of 5 Orange and State of New York, have invented certain new and useful Improvements in Mechanical Starters for Internal-Combustion Engines, of which the following is a specification.

10 My invention relates to mechanical starters for internal combustion engines and more particularly to mechanical starters for small aeronautical motors.

The starter *per se*, instead of projecting 15 without and beyond the exterior lines of the motor (as viewed from either the front or rear) is so related thereto as to occupy the space at one end of the V formed by the motor cylinders. Thus positioned, the starter 20 offers no resistance, whatsoever where the motor is streamlined, and may be, if desired, entirely inclosed within the motor cowling. Heretofore, no consideration whatsoever has been given in this regard. Moreover, by positioning the starter as intimated, it is entirely practical to support the mechanism thereof upon the motor crank case so that the engine bearers, and not the longérons or 25 other structural elements of the fuselage, bear the operating stresses.

The starter itself comprises a plurality of gears and shafts, a gear segment, a lever, a clutch, an operating cord and a bearing of special design. The bearing or standard 30 rests directly upon a projection formed on the motor crank case and adjacent to its free end supports two of the mentioned shafts. Upon one of these shafts the gear segment and the lever arm are mounted, and upon 35 the other of the shafts two of the gears (the gears being of different diameter) are mounted. The smaller of these gears is in mesh with the gear on the first mentioned shaft. The gear of larger diameter is connected 40 with the crank shaft of the motor. Accordingly, by exerting a pull on the operating cord which is attached to the free end of the lever, the motor crank shaft is turned over and the engine started. The 45 clutch provided is to release the starter mechanism after the engine is operating under its own power. Should one operation of the starter mechanism fail to start the motor a return spring, connected with the free 50 end of the lever, is provided to return the starter mechanism to its original position.

Thus returned, the starter mechanism may be again or repeatedly operated.

Of the drawings, wherein like characters of reference designate like or corresponding parts,

Figure 1 is a plan view of an airplane fuselage showing the relative arrangement of the motor and mechanical starter,

Fig. 2 is a rear end elevation of the motor plus the starting mechanism, and,

Fig. 3 is a side elevation of the motor and starting mechanism as illustrated in Fig. 2.

In the embodiment of the invention selected for illustration, only the nose end of an airplane fuselage, designated in its entirety by the numeral 10, is illustrated. The fuselage comprises longérons 11, fuselage struts 12, and wiring 13. Within and at the extreme forward end of the fuselage the 75 motor 14 is inclosed. The motor illustrated is of the four-cycle two cylinder V-type, the cylinders of which are designated as 15 and the crank case of which is designated as 16.

At one end, the crank case 16 of the motor 80 is enlarged or projected rearwardly as at 17 to support upon the projection thus formed, an upright bearing 18 bolted to the crank case projection as indicated. In the absence of a better term, the bearing 18 will be herein- 85 after referred to as a "double bearing." Two shafts are journaled in the bearing. One of these shafts, designated as 19, carries a lever arm 20 on one side of the bearing and a gear segment 21 on the opposite side 90 thereof. The axis of the shaft, if extended, would extend into the V space between the motor cylinders. The other of the shafts journaled in the double bearing is designated as 22. This shaft carries a small gear or 95 pinion 23 the teeth of which are in mesh with the gear segment 21. It also carries a comparatively large gear or sprocket 24, the diameter of which is several times the diameter of the small gear or pinion. This 100 large gear or sprocket 24 is directly connected by a chain 25 with a small gear or sprocket 26 mounted on a stub shaft 27, which in turn is provided with an overrunning clutch connection 28 between the shaft 105 27 and the sprocket wheel 26. Accordingly, as the large gear 24 is rotated by movement of the lever arm 20 the motor is turned over.

To the free end of the lever arm 20 an 110 operating cord 29 is connected. The cord 29 extends out laterally from the lever to a

guide 30, over which it passes. From the guide 30 the operating cord extends downwardly to a guide 31 and thence inwardly to a guide 32 carried by one of the cross struts of the fuselage. From the guide 32 the operating cord extends rearwardly for connection with a pivoted foot pedal or lever 33 conveniently located in the pilot's cockpit at one side of the foot control mechanism usually provided in aircraft. By exerting a push on the lever or pedal 33 the operating cord is pulled inwardly and the lever arm 20 given a fractional turn. As the lever arm is rotated, motion is transmitted to the gear segment 21 which in turn operates the chain connection between the sprocket 24 and the sprocket 26. By providing a proper ratio between the connected gears and sprockets the crank shaft is made to rotate several complete revolutions. Ordinarily several revolutions of the crank shaft are sufficient to start the motor.

Upon releasing the foot pressure on the lever 33 the lever arm 20 is brought back to its original position by a return spring 34 connected at one end with the free end of the lever and at its opposite end with one of the longérons 11 of the fuselage. The return spring, it will be noted, extends off from the lever in a direction opposite to that of the operating cord. Consequently, the pull exerted on the lever by operation of the foot pedal is directly against the action of the spring. The overrunning clutch connection between the stub shaft 27 and the sprocket wheel 26 automatically throws out the starter mechanism the moment the motor begins to operate under its own power.

From the foregoing it will be noted that a mechanical starter of the character described is simple of construction, compact, and easy of installation. Its relative arrangement with respect to the motor cylinders and to the projected end of the crank case is such that the engine bearers or motor supports receive the operating stresses and the motor cylinders shield it from the direct line of air rush under conditions where the motor is exposed. Ordinarily, the motor is streamlined, and under such circumstances the starter mechanism may be readily streamlined with the motor due to its proximity to the cylinders and due to the further fact that the starter mechanism lies entirely within the limits defined by the exterior lines of the motor as viewed from either the front or the rear.

While I have described my invention in detail in its present preferred embodiment, it will be obvious to those skilled in the art after understanding my invention, that various changes and modifications may be made therein without departing from the spirit or scope thereof. I aim in the ap-

pended claims to cover all such modifications and changes.

What is claimed is:

1. In a mechanical starter for internal combustion engines, the combination with a V type motor having a crank case projection at one end and a crank shaft extended into the crank case projection, of an upright bearing mounted upon the crank case projection, a shaft journaled in said bearing, the relative arrangement of the shaft to the engine cylinders being such that the axis of the shaft if continued would extend into the space defined by the inner walls of the motor cylinders, a lever arm mounted on said shaft, a gear segment mounted on said shaft, 80 a second shaft journaled in said bearing below and in parallelism with the first mentioned shaft; a gear mounted on this second shaft, said last mentioned gear and the gear segment being at all times in mesh, a connection between said last mentioned gear and the crank shaft for rotating the latter by movement of the lever arm, operating means connected with the lever arm, and a spring for returning the lever arm to its original position subsequent to each operation.

2. In a mechanical starter for internal combustion engines, the combination with a V type motor having a crank case projection at one end and a crank shaft extended into the crank case projection, of an upright bearing mounted upon the crank case projection, a shaft journaled in said bearing, the relative arrangement of the shaft to the engine cylinders being such that the axis of the shaft if continued would extend into the space defined by the inner walls of the motor cylinders, a lever arm mounted on said shaft, an operating cord connected with the lever arm, an operating lever located remote from the engine, one end of the operating lever having a connection with the operating cord for imparting movement to the lever arm, a gear segment mounted on said shaft, a second shaft journaled in said bearing below and in parallelism with the first mentioned shaft, a gear mounted on said second shaft, said last mentioned gear and the gear segment being at all times in mesh, a connection between said last mentioned gear and the crank shaft for rotating the latter by movement of the lever arm, and a return spring connected to the lever arm to return the starter mechanism to its original position subsequent to each operation of the operating lever.

In testimony whereof I affix my signature in the presence of two witnesses.

FREDERICK D. WARNER.
